Des. 230,247

Patented Feb. 5, 1974

230,247

GARDEN TOOL

Richard K. Parry, St. George, Utah
(2855 Canonita Drive, Fallbrook, Calif. 92028)

Filed Feb. 14, 1972, Ser. No. 226,395

Term of patent 14 years

Int. Cl. D8—05

U.S. Cl. D8—6

FIG. 1 is a rear perspective view of the garden tool with the handle shown in broken lines for purposes of illustration only;

FIG. 2 is a view in side elevation.

FIG. 3 is a top plan view, and

FIG. 4 is a front view.

I claim:

The ornamental design for a garden tool, as shown and described.
